C. W. WATKINS.
CAR HOLDING RATCHET.
APPLICATION FILED FEB. 19, 1921.

1,409,264.

Patented Mar. 14, 1922.

UNITED STATES PATENT OFFICE.

CHARLES WALTER WATKINS, OF DORRANCETON, PENNSYLVANIA.

CAR-HOLDING RATCHET.

1,409,264.

Specification of Letters Patent. Patented Mar. 14, 1922.

Application filed February 19, 1921. Serial No. 446,286.

To all whom it may concern:

Be it known that I, CHARLES W. WATKINS, a citizen of the United States, residing at Dorranceton, Kingston Station, in the county 5 of Luzerne and State of Pennsylvania, have invented certain new and useful Improvements in Car-Holding Ratchets, of which the following is a specification, reference being had to the accompanying drawings.

10 This invention relates to car-holding ratchets for car hauls of mines, pleasure rail-ways and the like.

An important object of the invention is to provide a device of this character which will 15 effectually prevent downward movement of a car, or analogous device upon inclines, and is particularly devised for preventing the accidental return of a car down an incline up which it is being hauled.

20 A further object of the invention is to provide a device of this character which may be applied to trestles and the like without cutting away of the framework thereof, so that the structure of the trestle is not altered 25 in such manner as to permit articles falling from the car to pass therethrough.

A still further object of the invention is to provide a device of this character which may be employed as a guard rail to keep the 30 cars on the track.

35 A further object of the invention is to provide a device of this character of such construction that it may be installed in as-sembled sections by the simple expedient of bolting down the sections on the inclined plane upon which they are to be employed.

40 A still further object of the invention is to provide a device of this character embody-ing ratchet teeth pivotally mounted upon a suitable supporting member, the ratchet teeth being of such structure that they assist one another in their return movements from the inoperative to the operative positions.

45 Further objects and advantages of the in-vention will become apparent throughout the course of the following description.

In the accompanying drawings, wherein 50 for the purpose of illustration is shown a preferred embodiment of my invention and 55 wherein like reference characters designate like parts throughout.

Figure 1 is a side elevation partly in sec-tion showing my ratchet device applied to

an inclined railway, the solid lines indicat-ing the position of the ratchet members 55 when the engaging member carried by the vehicle is initially depressing one of the ratchet members, the dotted lines illustrat-ing the position assumed by the members upon a continuation of the depression; 60

Figure 2 is a fragmentary plan view thereof;

Figure 3 is a section on the line 3—3 of Figure 1, and

Figure 4 is a section on the line 4—4 of 65 Figure 3.

Referring now more particularly to the drawings, the numeral 10 indicates the guard rail plate which may be secured to the incline 11 upon which it is employed in 70 any desired manner, this being shown in the present instance as comprising the bolt 12 extending through the structure of the plate, the guard rail and through a metal face plate 13 arranged upon the upper surface 75 of the guard plate.

Formed in one side of the guard rail 10 are recesses combining with the plate to form spaced inclined walls 14. Ratchet tooth members are provided each comprising 80 a counterweighted portion 15 and a tooth portion 16, the counterweighted portions 15 being provided with a face 17 adapted to engage against the inclined face 14 of the recesses when the ratchet members are in 85 the operative position. The upper ends of these inclined walls, designated by the nu-meral 14^a are adapted to coact with the ratchet members to limit their movement into the inoperative position. As is well 90 known to those familiar with the art, when a car is moving over a ratchet mechanism at considerable speed, the tendency would be to overthrow these ratchet members in such a manner that they would not return to their 95 normal position and this tendency to over-thrown is effectually prevented by the coac-tion by the upper ends 14^a of the inclined walls with the ratchet members as described.

Pivot bolts 18 extend through the coun-terweighted portions 15 of the ratchet tooth members and each embody an enlarged head 19 engaging the side face of the counter-weighted portion 15 and the pivot portion 20 upon which the ratchet tooth member ro-tates. This pivot portion 20 is reduced to 100 105

and forms a shoulder which abuts a washer 21 against the face of the guard plate 10 within the recesses, the reduced portion of the bolt 18 extending through the guard plate 10 and being secured thereto by a nut 22 countersunk in the opposite face of the guard plate.

In instances where the ratchet members are sufficiently closely spaced as upon a sharp incline, the tooth portions 16 of the ratchet members are made of sufficient length that the point or bill 23 thereof overhangs or falls within the path of movement of the extremity 24 of the counterweighted portion 15 of the next succeeding ratchet member. By this arrangement I am enabled to overcome any tendency of the ratchet members to remain in the inoperative position, a condition often occurring in mine railways where a considerable amount of dust is precipitated from the cars upon the ratchet members by reason of the fact that the point or bill 23 lying in the path of movement of the rear end of the counterweighted portion 25 is engaged by this counterweighted portion as the same moves to inoperative position and is accordingly given an initial return movement toward inoperative position sufficient to bring into play the full weight of 30 the counterweight to complete the return movement. In order that the ratchet members may be properly lubricated I form in the counterweighted portion 15 thereof an oil opening 16^a communicating with the bore 35 in which the portion 20 of the bolt 18 extends.

In the operation of my device as the car passes on upwardly the next tooth is depressed, first imparting to the first tooth 40 an initial impulse to return the same to the operative position with the tooth 16 thereof in position to engage the axle A in event of rearward movement of the car. This operation is repeated by each tooth in turn as the 45 car passes over the ratchet and if the car is provided with a plurality of tooth engaging members the operation is repeated at the passage of each engaging member thereover. Particular attention is drawn to 50 the fact that the movement of the ratchet members in both directions is positively limited, thereby preventing the ratchet members, when moving to the inoperative position, being overbalanced in such a manner 55 that they will remain in the inoperative position.

While I have described the use of but a single guard plate and ratchet mechanism, it will be obvious that where desired a plurality of these plates may be employed having their teeth arranged in staggered relation so that the rearward movement of which a car may partake before it is engaged by one of the teeth may be reduced to any desired limit.

It will further be obvious from the foregoing that my ratchet mechanism is particularly well adapted for use in connection with car hauls of the type described by reason of the fact that the teeth of the ratchet coact 70 to shift one another from the inoperative to the operative position and by reason of the fact that the wall 14 positively limits the movement of the ratchet members in both directions, thereby assuring correct positioning of the ratchet members. Since the structure as hereinbefore set forth is capable of some change and modification without materially departing from the spirit of my invention, I do not limit myself to 80 such specific structure except as hereinafter claimed.

What I claim is:

1. The combination with a vehicle operating upon a track, of a guard plate arranged adjacent the track, a plurality of pivotal members carried by the guard plate normally barring passage of the vehicle in one direction and shifting about their pivots to permit passage of the vehicle in the opposite direction, each of said members when it is shifted engaging the preceding member to return the same to normal position.

2. The combination with a vehicle operating upon a track, of a guard plate arranged adjacent the track and provided in one side face thereof with recesses forming spaced inclined side walls, a member pivotally connected with the guard plate adjacent each of said inclined walls and each embodying a portion adapted to engage the wall whereby its pivotal movement is limited, said members barring passage of the vehicle when said portions are in engagement with said inclined walls, said members when shifted about their pivots to move the said portions from engagement with said inclined walls each engaging the preceding member to impart thereto an initial movement tending to return the same into the position in which the said portion thereof engages said inclined wall.

3. The combination with a vehicle operating upon a track, of a guard plate arranged adjacent the track and provided in one side face thereof with recesses forming spaced inclined walls, ratchet members pivotally connected with the guard plate adjacent each of said inclined walls and each embodying a counterweighted portion and a tooth portion, said ratchet members when in the operative position having the tooth portions thereof positioned to bar passage of the vehicle upon the track in one direction, said counterweighted portions each embodying a face engaging its coacting inclined wall when the ratchet member is in the operative position, said ratchet members being engaged by the vehicle in moving in the opposite direction to be shifted thereby to in-

operative position, said ratchet members embodying portions engaging the upper end of the coacting inclined wall when the ratchet members move to the inoperative position 5 whereby such movement is limited, the bill of the tooth portions of each of said ratchet members lying in the path of movement of

the counterweighted portion of the next succeeding ratchet member when the ratchet member is in the inoperative position. 10

In testimony whereof I hereunto affix my signature.

CHARLES WALTER WATKINS.
